UNITED STATES PATENT OFFICE.

FREDRICK JAMES SIMPSON, OF MONTREAL, QUÉBEC, CANADA, ASSIGNOR TO THOMAS P. SHELLY, OF MONTREAL, QUÉBEC, CANADA.

DIE FOR BOLT-MAKING OR SIMILAR MACHINES.

Application filed August 3, 1923. Serial No. 655,440.

This invention relates generally to the manufacture of bolts, rivets and the like either hot or cold by the upsetting method, and relates more particularly to a process of 5 and apparatus for making such articles.

One of the objects of the invention is to provide for the upsetting of the metal in such a manner that the articles will be substantially perfectly formed in the upsetting, 10 the production of fine or other blemishes being avoided, also the necessity of subsequent trimming, sizing or shaping operations.

A further object is to provide for the making in a single operation of articles which 15 are now ordinarily made in two or more operations, thereby increasing the rate of production or simplifying the manufacture or both, as compared with existing practice, without, however, confining the invention to 20 single operation methods.

A still further object is to provide for an increase in the rate of production as compared with existing conditions, additional to the increase arising from the reduction in 25 the number of operations.

Another object is to provide for the manufacture of articles as aforesaid, using existing machinery, by the provision of special dies or other apparatus.

30 Another object is the provision of dies embodying relatively adjustable and renewable parts, whereby changes in the dimensions or shape of the product may be effected by adjusting parts of the die or substituting other parts, without changing the whole die.

Another object is to provide for certain and positive ejection of the finished articles from the forming die, whereby damage to or 40 interruption of the operation of the machine may be avoided.

Still another object is to provide a die yieldingly mounted to guard against breakage of the die or machine in the event of an 45 unforeseen obstruction in the path of movement of the die.

Various other objects and advantages may be ascertained from the following description and drawings, which, for convenience of 50 explanation, have relation to the manufacture of bolts, but to which particular article of manufacture the invention is not limited.

Upsetting machinery of the class to which this invention has relation comprises, generally speaking, gripping dies to hold material

to be upset and a head or ram movable toward and away from the gripping dies to carry upsetting or heading dies into and out of engagement with the material. The heading die or dies generally used on these machines are, for the most part, solid dies formed with a recess of the exact size and shape of the head to be formed, so that if it is desired to produce any variations in the bolt heads it is necessary to provide a fresh die for each variation, even if such variation is only in the thickness of the head. When making bolts of larger size or bolts in which the head is larger than usual relatively to the body of the bolt it is usually necessary to form the head in two or more operations owing to the impracticability of causing the metal to flow in the manner necessary to form the head in a single upsetting operation. This is especially true of bolts with 60 relatively large heads and is due to the fact that the relatively large amount of metal projected beyond the gripping dies and unsupported has a tendency to double up rather than to expand in diameter in the first part 65 of the upsetting operation, with the result that imperfectly formed heads are produced. In the manufacture of such bolts it has been found necessary or advisable to perform the 70 upsetting in two stages, the dies used in the first upsetting operation being such that doubling up or bending of the projecting stock bar is largely prevented and a preliminary upsetting obtained to yield an intermediate 75 form which is capable of withstanding the final upsetting operation without bending.

When performing the upsetting in either one or more operations the formation of fins or flash at the under surface of bolt heads seems 80 inevitable and is now found to be due to the fact that the metal expands or swells during the first part of the upsetting in the space 85 between the relatively approaching gripping and heading dies to a greater size than the recess in the heading die. The metal 90 which projects beyond the recess of the heading die is eventually caught between the faces of the heading die and the gripping die and squeezed out to form the fin or flash. The foregoing conditions have the effect of limiting the speed at which the heading die may be moved, the tendency to mal-formed heads increasing as the speed of operation increases.

According to the present invention the 110

metal to be formed or upset is first completely enclosed in the die by bringing the heading and gripping dies into contact before any appreciable amount of upsetting occurs. The recess or chamber provided in the heading die to receive the metal to be upset is larger in volume than the metal and the upsetting is performed by contracting this chamber or recess. Owing to the fact that the heading and gripping dies are in contact before the upsetting commences it is impossible for the metal to be caught between the faces of the dies and formed into the objectionable flash. The metal flows least readily adjacent the gripping dies and unless an excess of metal is provided it will not flow into any minute crevice that may exist between the heading and gripping dies. The result is a complete absence of flash on the underside of the head. This applies equally to upsetting performed in one or more than one operation. In addition to preventing the formation of flash on the heads, the complete enclosure of the metal from the very commencement of the upsetting serves to support that part of the metal which in the old method is unsupported between the gripping and heading dies. The bending of the metal is thus limited to only a slight deflection which is not detrimental.

In one embodiment of the invention, the heading die is constructed of relatively movable parts which unite to define a collapsible recess for reception of the metal to be upset, which recess is collapsed or reduced in size by relative movement of the parts. When the die is empty the stock receiving and heading recess thereof is almost entirely occupied by the heading plunger which advances with the die to engage the end of a stock bar projecting from gripping dies. Movement of the plunger is checked by its engagement with the stock but the die continues to advance until its movement is arrested by contact with the gripping dies. The projecting end of the stock bar is thus completely enclosed before any substantial upsetting occurs. After movement of the die stops the plunger advances through the die to perform the upsetting operation. During the retreat of the die the plunger advances to its original position relative to the die and ejects the finished bolt from the die. Means is provided for yieldably supporting the die in the reciprocating head of the machine so that in the event of any unforeseen obstruction between the heading and gripping dies the heading die may yield to avoid damage to itself or the machine.

In the accompanying drawings various embodiments of the invention have been illustrated, but it will be understood that the invention is not thereby limited to these particular embodiments but embraces all other

embodiments by means of which the invention may be carried into practice, as well as minor modifications of the embodiments herein illustrated and described.

In the drawings, presenting as aforesaid only certain embodiments of the invention:—

Fig. 1 is a longitudinal section through the centre of a heading die showing the same in retracted or inoperative position.

Fig. 2 is a fragmentary view similar to Figure 1, showing the position of the parts at the commencement of upsetting.

Fig. 3 is a fragmentary view similar to Figure 1 showing the die in the advanced position occupied at the completion of the formation of a bolt head.

Fig. 4 is a view similar to Figure 1, illustrating certain modifications.

Fig. 5 is a face view of the die.

Referring more particularly to the drawings, and especially to Figures 1, 2 and 3 thereof, 11 designates a die carrier adapted for insertion in the reciprocating head of a bolt making or other suitable machine. A die holder 12 is provided carrying a die 13 which is preferably an integral plug of metal having a recess 14 therein shaped according to the product desired. This die is provided with a passage 15 leading from the bottom of the recess 14 through to the back of the die and adapted to slidably receive an upsetting plunger 16. The diameter of the passage 15 and of the plunger 16 must be at least as great as the diameter of the stock bar to be upset but may be greater, as shown. The die is seated in the holder 12 in any suitable way and held in position on its seat by means of a ring 17 secured to the holder or by any other suitable means.

Behind the die holder the carrier carries a slidable cushion ring 18 urged forwardly by heavy springs 19 and restrained in its forward movement by headed screws 20 connected to the ring and engaging the carrier. The springs 19 are sufficiently stiff to hold the cushion ring substantially without movement relatively to the carrier during the operation of the device, with the result that the cushion ring may be properly and is herein considered as part of the carrier. The die holder is yieldingly mounted on the carrier by means of springs 21 positioned preferably by seating the ends thereon in recesses 22 in the holder and cushion ring. Guide pins 23 may be provided to hold the springs against buckling when under compression. The forward movement of the die holder under influence of the springs 21 may be limited in any suitable way; for example, by means of headed screws 24 connected to the cushion ring and slidably engaged with the holder.

In order to keep the diameter of the holder as small as possible, the springs 21 are preferably individually of small size and the de-

sired stiffness of mounting is obtained by employing a considerable number of such springs. If additional stiffness in the mounting is required it may be obtained, if space permits, by the provision of additional springs 25 seated in recesses 26 in the die and carrier.

The upsetting plunger 16 is removably mounted in a holder 27 slidably mounted in the carrier. One convenient method of effecting this mounting is to provide a head 28 at the rear end of the plunger and an annular nut 29 to overlie the head and to be screwed to the forward end of the holder. The plunger holder is yieldably mounted in the carrier by means of a spring 30 in compression between the holder and a plug 31 screwed or otherwise adjustably secured in the carrier. This plug serves also as a seat to limit rearward movement of the plunger and its holder in the carrier and is of sufficient strength to sustain the load incident to the upsetting operation. The spring 30 as illustrated is mounted within the holder and supported against buckling by a pin 32 on the plug, but it will be understood that this particular disposition of the spring may be departed from.

To protect the springs 19 and 21 from damage; to prevent an obstruction coming between the spring supported bodies, and to impart a neat appearance to the device, sleeves 33 may be provided on the cushion member slidably engaging the die holder and on the carrier slidably engaging the cushion ring.

Gripping dies to hold a stock bar to be upset are designated 34, and the projecting portion of the stock bar sufficient for upsetting or heading is designated 35.

A modification of the method of mounting the plunger is illustrated in Figure 4. The plunger holder is in effect integral with the adjacent plug and the plunger is movable in the holder. The holder proper, designated 27^a, is provided at the rear with a threaded portion 31^a screwing into the carrier. The plunger nut 29^a is increased in length to provide for travel of the plunger head therein and the plunger spring 30^a is in compression between the plunger head and a plug 36 screwed or otherwise adjustably secured in the rear end of the holder.

The normal or idle position of the parts is illustrated in Figures 1 and 4; that is to say, the die and its holder are advanced beyond the carrier by the action of the springs 21 and 25 to the limit of movement determined by the setting of the screws 24 and the plunger is advanced until its end is substantially flush with the face of the die, so that it occupies the central part of the heading recess 14. In the construction shown in Figure 1 forward movement of the plunger is limited by engagement of its holder with

the rear face of the die, while in the embodiment shown in Figure 4 this movement is limited by the nut 29^a. The cushion ring is also in its normal advanced position as already described. When a proper length of stock bar has been projected beyond the gripping dies and is securely held against retreat by these dies, the whole heading device is advanced by the reciprocating head of the machine. In the early part of this advance the end of the plunger 16 engages the end of the stock bar and advance of the plunger is thereby stopped but the remainder of the device advances and the plunger is relatively retreated through the die and into the carrier. This movement continues until the back end of the plunger holder comes in contact with the plug 31. When the parts are properly adjusted the face of the heading die engages the gripping dies at substantially the same instant that relative retreat of the plunger is checked. The spring 30 behind the plunger, is, comparatively speaking, weak, with the result that its compression by the relative retreat of the plunger does not apply sufficient pressure to the plunger to cause any appreciable or substantial upsetting action even if the stock bar 35 is very hot and quite soft. The position of the parts is illustrated in Figure 2 and it will be seen that the stock bar to be upset is now completely enclosed in the heading die.

As the carrier 11 continues to advance it drives the plunger forwardly through the now stationary heading die to upset the metal enclosed in the die. In this movement the heading die relatively retreats toward the carrier and plunger or conversely the plunger and carrier advance relatively to the heading die, the springs 21 and 25 being compressed. The cushion springs 19 behind the cushion ring are so much heavier than the springs 21 and 25 that they do not yield appreciably during compression of the lighter springs. Position of the parts at the completion of the heading operation is illustrated in Figure 3.

The machine head now retreats the whole device and the parts assume their original relation by the action of their respective springs. In assuming its original position the plunger ejects the product from the heading die, this being facilitated where the nature of the product permits by a slight flaring of the side walls of the die recess, which flaring is illustrated to an exaggerated degree.

If any obstruction should occur between the gripping dies and heading die, the heading die will retreat and if the space between the die holder and cushion ring is not sufficient to compensate for the thickness of the obstruction the cushion ring will then retreat with the die holder. In this way breakage

of the device or of the machine will be largely or wholly prevented.

When a different size or shape of head is to be made, the die 13 and plunger 16 are exchanged for corresponding parts of the desired size and shape and the plug 31 adjusted to regulate the movement of the plunger. The screws 24 may also be adjusted to regulate the position of the die relatively to the plunger. The modification shown in Figure 4 has the advantage over the form shown in Figure 1 that the tension of the plunger spring may be adjusted without changing the plunger. It has previously been stated that the plunger may be of any suitable size and this must be held to include a plunger of the full dimensions and shape of the heading recess as shown, for example, in Patent No. 1,111,729, September 29, 1914. Such an arrangement will have an advantage over the form of die illustrated, in that thickness of the heads formed may be regulated merely by adjustment of the plunger.

In its broad aspect the invention relates to the relative movement of the plunger and heading die and it must be understood that the invention is not confined for the effecting of these movements to the particular means disclosed, but contemplates employment of any suitable means to effect the desired relative movement.

In addition to the advantages of superior head formation pointed out in the preceding description, it is to be noted that the use of this process and die, which positively prevents the formation of fins or flashes on bolt heads, thereby eliminates the trimming operation, and by reason of the fact that the heads may be made very accurately to size, it becomes unnecessary even to subsequently size the heads. This feature greatly reduces the cost of manufacturing bolts and the like and has the additional advantage of avoiding the rough knife-edges which exist where bolt heads are sized or trimmed to remove the flash. The support afforded to the stock bar during the upsetting process enables the speed of operation to be increased, and in many instances where it has been customary or necessary to make the head in two operations, employment of the present process and apparatus will enable such heads to be made in a single operation. It must not be concluded, however, that this invention is confined to heading dies, as it is applicable equally well to the preliminary forming dies in cases where it is necessary to make the heads in two or more operations.

While only the manufacture of bolts has been dealt with in the foregoing description, it will be understood that the invention is not thus limited, but is applicable equally to the formation of rivets and any other articles capable of being formed in the same or a similar way.

Generally throughout the description the heading device has been described as advancing to the gripping dies and material, but it is to be understood that this is not absolutely essential, as the heading device may be stationary and the gripping dies and stock advanced into engagement therewith. In other words, the term "advanced" has been used in the description and in the following claims merely to indicate the relative movement or approach of the parts concerned and it is therefore to be understood that the invention is not to be considered as limited to advance of the heading means in the strict sense of the term, but rather in the broad sense herein indicated.

A peculiarity of this device, which I attribute to the use of a plunger of greater diameter than the stock bar and of almost as great diameter as the head to be formed, is that the head appears to crown perfectly with little or no contact with the bottom of the heading recess 14. This enables the heading recess to be formed slightly larger in volume than the bolt head to be made and therefore slightly larger in volume than the proper amount of stock bar fed from the gripping dies. This is a very valuable feature as it protects the die against damage due to excessive feeding of the stock bar and also protects the bolt heads against mal-formation from the same cause. If the stock bar is overfed to a small extent, as often happens, the only result is a slightly thicker head crowned by intimate contact with the bottom of the recess 14.

Having thus described my invention, what I claim is:

1. In forming machinery for bolts and the like, in combination with gripping dies to hold material against retreat during a forming operation, a forming die, a carrier to advance the forming die into contact with the gripping dies to enclose material prior to forming and an upsetting plunger in the forming die connected to said carrier and adapted to remain stationary upon contact with material until the material is enclosed in the forming die, and a stop adjustable in the carrier behind the plunger whereby the plunger is subsequently advanced by the carrier relatively to the forming die to upset material therein.

2. In forming machinery for bolts and the like, a die having a forming recess, an upsetting plunger slidable in said die, a reciprocatable carrier common to said die and plunger to simultaneously advance the die and plunger to the material to be formed and to successively advance the die and plunger each while the other is stationary to first enclose the material and subsequently upset the enclosed material.

3. In forming machinery for bolts and the like, a die having a forming recess therein,

- an upsetting plunger slidable in the die, and a reciprocatable carrier common to said die and plunger to advance the die and plunger simultaneously until engagement of the plunger and material occurs, and to then advance the die alone to enclose the material and to finally advance the plunger alone to upset material enclosed in the die. 5
4. In forming machinery for bolts and the like, the combination with gripping dies to hold material against retreat during forming, of a die having a forming recess, an upsetting plunger slidable in said forming die, means to advance the forming die and plunger simultaneously to the material until engagement of material and plunger occurs and to then advance the forming die alone into engagement with the gripping dies to enclose the material and to finally advance the plunger alone to upset material enclosed in the forming die and resilient means to restore the carrier, die and plunger to their original relations upon retreat of the carrier. 10
5. In forming machinery for bolts and the like, a reciprocatable carrier, a plunger and a forming die mounted on the carrier for movement thereby, independent yieldable connections between the carrier and plunger and between the carrier and die permitting cessation of plunger and die advance during continuous carrier advance, said plunger and carrier being adapted for direct engagement to positively advance the plunger relatively 15 to the die. 25
6. In forming machinery for bolts and the like, a reciprocatable carrier, a plunger and a die mounted thereon, the plunger being slidable in the die, yieldable connection between the carrier and plunger permitting relative retreat of the plunger into the die to give place to material to be formed and yieldable connection between the carrier and die to permit relative advance of the plunger 20 in the die to upset material in the die. 45
7. In forming machinery for bolts and the like, a forming die, a plunger movable through the die to upset material therein, a plunger carrier and yieldable connection between the plunger and carrier to be compressed prior to upsetting and to expand after upsetting and advance the plunger through the die to eject formed material therefrom. 50
8. In forming machinery for bolts and the like, a carrier, a forming die yieldably mounted thereon for limited movement relatively to the carrier and a normally rigid cushioning means between the die and carrier adapted to yield and permit increased relative movement of the die and carrier in case of an obstruction in the path of the die. 55
9. In forming machinery for bolts and the like, a carrier, a die holder, springs between the carrier and holder, a die in the 60
- holder, a plunger slidable in the carrier and through the die, a spring between the plunger and carrier, and means to limit movement of the holder, and plunger due to action of the springs. 70
10. In forming machinery for bolts and the like, a carrier, a die holder, springs between the carrier and holder, a die in the holder, a plunger slidable in the carrier and through the die, a spring between the plunger and carrier, and an adjustable seat in the carrier for said plunger. 75
11. In forming machinery for bolts and the like, a carrier, a die holder, springs between the carrier and holder, a die in the holder, a plunger slidable in the carrier and through the die, a spring between the plunger and carrier and adjustable means to regulate the amplitude of movement of the plunger relative to the carrier. 80
12. In forming machinery for bolts and the like, a carrier, a cushion ring slidable thereon, springs between the carrier and cushion ring urging the ring forwardly on the carrier, a die, and springs between the die and cushion ring urging the die forwardly of the carrier, said die springs being less resistant to compression than the cushion ring. 85
13. In forming machinery for bolts and the like, a carrier, a die holder thereon, a die removably mounted in said holder, a plunger holder mounted in the carrier for movement thereby and a plunger removably mounted in the holder and slidable in the die. 90
14. In forming machinery for bolts and the like, a carrier, a cushion ring and a die independently reciprocatable on the carrier, springs between the ring and carrier and between the die and ring, and sleeves on the carrier and ring enclosing said spring and slidably receiving the ring and die, respectively. 95
15. In forming machinery for bolts and the like, the combination with gripping dies to hold material against retreat during forming, of a forming die movable into a position of rest against the gripping dies to enclose material prior to upsetting, a plunger relatively slidable in the die and movable with the die to a position of rest against the material during the first part of the die movement and subsequently movable independently of the die to upset material therein, and means to move said die and plunger intermittently in the manner aforesaid. 100
16. In forming machinery for bolts and the like, the combination with gripping dies to hold material against retreat during forming, a forming die and a plunger relatively slidable therein, and means to move the plunger to a position of rest against the material and to subsequently move the die to a position of rest against the gripping die. 105
- 120
- 125
- 130

dies and while the plunger is stationary and to finally move the plunger to upset material in the die.

17. In forming machinery for bolts and the like, the combination with gripping dies to hold material against retreat during forming, a forming die and a plunger relatively slideable therein, and a single carrier for both the die and plunger, upon which the die and plunger are independently movable, to advance the plunger to a position of rest against the material and to subsequently

move the die to a position of rest against the gripping dies and to finally move the plunger to upset material in the die, and 15 means independent of the carrier to further advance the plunger relatively to the die and upon retreat thereof from the gripping dies to eject formed material from the forming die. 20

In witness whereof, I have hereunto set my hand.

FREDRICK JAMES SIMPSON.
